US00D454499S

(12) United States Design Patent (10) Patent No.: US D454,499 S
Berkhauer (45) Date of Patent: * Mar. 19, 2002

(54) BOTTLE

(75) Inventor: Elie Papiernik Berkhauer, Paris (FR)

(73) Assignee: Guerlain S.A., Paris (FR)

() Term: 14 Years

(21) Appl. No.: 29/129,676

(22) Filed: Sep. 19, 2000

(30) Foreign Application Priority Data

Mar. 20, 2000 (FR) 00 1746

(51) LOC (7) Cl. 09-01

(52) U.S. Cl. D9/535; D9/573

(58) Field of Search D9/503, 505, 516,
D9/530, 535, 541, 542, 559, 560, 307,
